UNITED STATES PATENT OFFICE

CHARLES F. SCHELL, OF BUFFALO, NEW YORK.

WATER-RADIATOR FOR AUTOMOBILES.

No. 895,205.

Specification of Letters Patent.

Patented Aug. 4, 1908.

Application filed January 9, 1907. Serial No. 351,558.

To all whom it may concern:

Be it known that I, CHARLES F. SCHELL, of Buffalo, in the county of Erie and State of New York, have invented certain new and useful Improvements in Water-Radiators for Automobiles, of which the following is a specification.

My invention relates to water-radiators, such as are used in conjunction with water-cooled motors in automobiles.

The objects of my invention are, to increase the water capacity of the radiator and provide storage capacity for water so that the frequent refilling of the radiator will not be necessary; to provide new and improved air-tubes; and to otherwise improve on water radiators of this type now in use.

To these ends the invention consists in the construction, arrangement and combination of parts to be hereinafter described and particularly pointed out in the appended claims.

In the drawings in which similar numerals of reference refer to similar parts:—Figure 1 is a front elevation of a radiator embodying my improvements. Fig. 2 is a horizontal section taken on line 2—2, Fig. 1. Fig. 3 is a central vertical longitudinal section through the radiator. Fig. 4 is a horizontal section taken on line 4—4, Fig. 3. Fig. 5 is a vertical section taken on line 5—5, Fig. 3. Figs. 6 and 7 are perspective views of a sheet of metal, preferably thin sheet copper, showing the manner of preparing the same to form the air tubes for the radiator. Fig. 8 is a perspective view of one of the air-tubes. Fig. 9 is a detached inverted perspective view of one of the bolt-blocks within the out-let chamber. Fig. 10 is a vertical longitudinal section of a radiator embodying my invention in modified form.

The reference numeral 10 designates the radiator casing which may be of any design and comprises a top wall 11, a bottom wall 12, end walls 13, a front wall 14 having a large central opening, and a rear wall 15 also provided with a large central opening corresponding in size and outline with the opening in said front wall.

Arranged parallel with the end walls and connecting the front and rear walls of the casing at the ends of the openings therein are transverse interior walls 16 which extend vertically from the top to the bottom of said

openings, forming water-spaces 17 and having their upper ends inclosed by horizontal walls 18; said water-spaces serving as storage-chambers. Located within the space formed by said openings are numerous air-tubes 19 arranged in horizontal rows and having the tubes in staggered relation from top to bottom. These tubes are provided with enlarged ends or collars 20 which lie in contact to provide intervening spaces 21 between the tubes of adjacent rows and between the tubes of each row, which spaces form narrow staggered water-passages. This arrangement, however, is not new, but the particular formation of the tubes herein shown is a very important feature of my invention. Each of the air-tubes 19 is formed of a sheet of thin copper having opposite marginal portions folded, as at 22, and then bent or curved at a right-angle to the folded ends to form a tube of the desired cross-sectional shape; the shape preferred being rectangular and preferably square, but if desired, the tubes may be cylindrical, octagonal, or of any other formation in cross-section.

In forming the tubes, the folded portions thereof are on the exterior and form integral exterior collars, and when assembling the same to form the radiator, the collars of adjacent tubes are in contact and united; thus forming the water-passages between the tubes. The latter are preferably soldered together at their enlarged ends and the collars thereof serve to close the ends of said passages. The width of the water-passages is governed entirely by the number of times the sheet copper is folded at opposite ends; but I have found that a double fold as shown in Figs. 6 and 7, on the gage of sheet copper usually employed for radiators of this type, answers the purpose admirably for the greater portion of automobiles now in use; but in some cases a single fold, causing a reduction in the width of the water-passages, or more than two folds, causing an enlargement of the water-passages, will be found more effective.

The air-tubes completely fill the openings in the front and rear walls of the radiator-casing, and serve as the lower wall of the inlet-chamber 23 at the top of the casing, and the upper wall of the outlet-chamber 24 at the bottom of the casing. From this it will

be understood that water-chambers are provided above, below, and at the sides of the assembled air-tubes.

As one of the important features of my invention is to increase the capacity for holding water, I provide for enlarging the outlet-chamber 24, by placing the bar-heads or blocks 25 of the securing-bolts 26 within said chamber, instead of placing them beneath the bottom 12 of the casing, as has heretofore been practiced. This permits me to use as a part of the outlet chamber, considerable space which has heretofore been wasted; thereby increasing the capacity for the cooling water without enlarging the radiator. As shown in Figs. 5 and 9, the bar heads or blocks 25 are provided on their under-sides with grooves 27 to permit the free circulation of water; said heads or blocks being of sufficient width to provide a good bearing and of a length to extend fully across the chamber with the ends thereof in contact with the front and rear walls of the casing. The shanks extend through openings in the bottom and are adapted to be passed through the frame of the automobile; nuts being applied to the ends of the shanks to securely affix the radiator to the frame.

For a more secure connection between the front wall of the casing and the interior walls 16, also between said front wall and the assembled tubes at the top and bottom, I provide angle-irons 28, each of which has one web thereof soldered and riveted to said front wall and its other web soldered to the interior walls 16, or to the tubes, as the case may be, and as clearly shown in Fig. 3. This makes a more perfect water-tight seam than has heretofore been provided at this point.

Within the inlet-chamber I arrange water inlet-pipes 29 having their lower or outlet ends soldered into openings in the walls 18 and their upper or inlet ends terminating a considerable distance above the air tubes 45 forming the bottom of the inlet-chamber. As is common in radiators of this type, a filling-opening 30 is provided through which water is poured into the radiator. The latter has connection with the water-jacket of the motor by suitable pipes connected to the inlet 31 of the inlet-chamber 23, and the outlet 32 of the outlet chamber 24.

The water enters the inlet-chamber and finds its way through the various water-passages 21 to the outlet, from whence it passes out to the water jacket of the motor through the outlet 32, and is pumped back into the inlet chamber 23 through the inlet 31 thereof, being in constant circulation and thoroughly cooled as it passes between the air-tubes through which the air passes. When first filling the radiator with the cooling water, the side or storage chambers 17 are filled from the bottom when the escape of the water from the outlet chamber is slower than

the supply thereto through the water-passages 21, and said storage-chambers are also filled from the top when the level of the water in the inlet chamber is even with or above the inlet ends of the inlet pipes 29, through which latter it flows and enters said storage chambers at 33.

When the water rises into the storage chambers 17 from the outlet-chamber and also enters said chambers through the inlet-pipes 29, provision must be made for the escape of air from said chambers. This I preferably do by means of air-escape pipes 34 located within the inlet-chamber and opening at one end into the storage chambers 80 through the upper walls 18 thereof; said air escape-pipes terminating at their other ends in a plane above the inlet-ends of the water inlet-pipes 29. If desired, the walls 18 at the upper ends of the side or storage chambers may each have one or more openings, such as shown at 35, through which water may be supplied to said chambers; these openings being used to more quickly fill the chambers.

The construction above described is the preferred embodiment of my invention, and is arranged that the water when first supplied to the radiator, must pass down between the air-tubes until the inlet-chamber is almost filled, after which it may also pass into the side storage-chambers through the inlet-pipes 29. When the small perforations 35 are formed in the walls 18 at the upper ends of said storage-chambers, the flow of water therethrough is much less than will pass through the water-passages 21, and therefore it will be permitted to rise to a point where it will overflow through the inlet-pipes 29; particularly as it is poured into the radiator much quicker than it can flow through the passages 21.

Another embodiment of my invention is shown in Fig. 10, in which the upper ends of the side storage-chambers are open and the interior walls 16, extended upward and inward into the inlet-chamber, as at 36. When so constructed the water will enter the side chambers from the bottom, and will also flow over the tops of the walls 16.

Having thus described my invention, what I claim is,—

1. A tube for radiators formed of a single piece of metal folded upon itself at opposite ends and thence bent at right-angles to the folded ends into the form of a tube.

2. A radiator comprising a plurality of assembled tubes, each tube being formed of a flat sheet of metal folded upon itself at one end and thence bent at right-angles into the form of a tube, said folded ends serving to separate the tubes to form water-spaces.

3. A radiator comprising a plurality of assembled tubes, each tube being formed of a single piece of metal folded upon itself at op-

posite ends and thence bent into tubular form with the folded ends on the outer sides, said folded ends separating the assembled tubes at points between their ends.

5 4. A radiator comprising a series of air-passages and water-passages, an inlet-chamber and an outlet-chamber connected by said water-passages, and storage-chambers in communication with said inlet and outlet-chambers.

5 5. A radiator comprising a series of air-passages and water-passages, an inlet-chamber and an outlet-chamber connected by said water-passages, and storage-chambers in communication with said inlet and outlet-chambers and located at opposite side of said air-passages.

6 6. A radiator comprising a casing having a series of tubes arranged to provide air-passages and water-passages, an inlet-chamber at the upper end of said casing and an outlet-chamber at the lower end thereof, said chambers being connected by said water-passages, and a storage-chamber opening into the outlet-chamber and having its inlet at the upper end at a point above the upper ends of said water-passages.

7 7. A radiator comprising a casing having an inlet-chamber at its upper-end, an outlet-chamber at its lower end, and a storage-chamber at each side in communication with said inlet and outlet-chambers, tubes bounded by said chambers and arranged to provide water-passages and air-passages, said water-passages connecting said outlet-chamber with said inlet-chamber, and means to pre-

vent the filling of said storage-chambers until the level of the water in the latter reaches a certain height.

8. A radiator of the character described 40 having an inlet-chamber, an outlet-chamber, air-cooled passages connecting said chambers, and bolts passed through the bottom of the outlet-chamber having enlarged heads bearing against the inner side of said bottom, 45 said bolts serving to secure the radiator to a foundation.

9. A radiator of the character described having an inlet chamber, an outlet chamber, air-cooled passages connecting said chambers 50 and securing-bolts passed through the bottom of the outlet-chamber and having bar-shaped heads extending the full width of said last mentioned chamber with grooves in the underside of said heads to permit the circulation of water therethrough.

10. A radiator comprising a casing having a top wall, a bottom wall, end walls, and a front and rear wall having each a central opening, interior walls connecting the front 60 and rear walls at opposite ends of said openings, a plurality of air-tubes providing water-passages and located between said interior walls, and angle-irons connecting the front wall with said interior walls.

65 In testimony whereof I have affixed my signature in the presence of two subscribing witnesses.
